[57] **CLAIM**

The ornamental design for a tire tread, as shown and
described.

DESCRIPTION

FIG. 1 is a perspective view of a tire tread, it being
understood that the pattern is repeated uniformly throughout
the circumference of the tread;

FIG. 2 is a front elevational view thereof;

FIG. 3 is a side elevational view thereof, the opposite side
elevational view being a mirror image therof; and,

FIG. 4 is an enlarged fragmentary front view thereof.
The broken lines defining the tire inner bead and the
peripheral boundary between the tire tread and the sidewall
are for illustrative purposes only and form no part of the
claimed design.
